UNITED STATES PATENT OFFICE

JOHN BOYKO, OF DETROIT, MICHIGAN, ASSIGNOR OF ONE-HALF TO NIKOLAS STEPANKOW, OF DETROIT, MICHIGAN

AUTOMATIC RAIL SWITCH OPERATING DEVICE

Application filed December 7, 1928. Serial No. 324,358.

The object of my invention is to produce a switch operating device that will open or close a rail switch point automatically, and while the car or engine operating on the 5 tracks is in motion.

Another object is to produce a rail switch operating device that will function at the will of an operator of an approaching car, and will move to alternately open and close 10 the rail switch point.

A further object is to produce a mechanical device that is positive in its movement, and will insure a complete opening or closing of the switch point before the approaching car 15 reaches the switch, and that is automatically operated by the car driver without stopping.

A still further object is to produce an automatic switch operating device that is simple in construction, easily and efficiently operated and that can be manufactured at a very 20 low cost.

These several objects are attained in the preferred form by the construction and arrangement of parts more fully hereinafter set 25 forth.

Similar parts on all drawings are marked by similar numerals.

Fig. 1 illustrates my device mounted on a railway track, with the operating member 30 attached to the forward end of an approaching car.

Fig. 2 is a detail side view of the operating member and supporting frame.

Fig. 3 is a front view of the same member 35 showing the relative position of the operating bar and frame members.

Fig. 4 is a top view of the same member showing the relative position of the bar and spring lifting means.

Fig. 5 is a plan view of the rail point operating mechanism showing the moving parts and means for attaching to the rail switch point.

Fig. 6 is a side view of the switch box 45 showing its exterior structure and means for attaching to the rail road ties.

Fig. 7 is an end view taken on the line 7-7 of the Fig. 5 showing the relative position of the operating mechanism to the rail 50 switch point.

Fig. 8 is a sectional view taken on the line 8-8 of the Fig. 5 showing the inner working member or switch bar and means for pivoting same within the inclosing switch casing.

Fig. 9 is a sectional view taken on the line 9-9 of the Fig. 5 showing the movement of the switch bar within the inclosing casing and means for connecting same to the rail switch point.

I will now describe more fully the detailed 60 construction of my device, referring to the drawings and the marks thereon.

The switch box —1— is preferably made of cast metal, rectangular in form, having ribbed side members —2— projecting along 65 each side thereof and provided with suitable bolt holes —3— for rigidly and securely attaching said casing to the rail ties —4— by either lag screws or rail spikes. The casing —1— is designed to be positioned near the 70 center of the track between the car rails —5— and parallel thereto, with one end placed approximately opposite the rail switch point —6—. The casing —1— is formed with a hollow V-shaped chamber —7—, having 75 vertical walls extending nearly the entire length of the casing. The larger end of said chamber being positioned opposite the rail switch point —6—, and with the smaller V-end of said chamber pointed in the same direction as said switch point. The casing —1— is also formed with a deep grooved recess —8— having vertical walls —9— positioned parallel to each other and to the center line axis of said casing and extending the entire 80 length thereof. The grooved recess —8— also intersects the V-shaped chamber —7— along its centerline, dividing same into separated halves. The vertical walls —9— act as guide bars for holding exterior member as 85 length therethrough in a predetermined path when passed through the V-shaped chamber —7—. Mounted within the chamber —7— is a solid V-shaped switch block —10—, formed with vertical walls, and 90 of a width approximately one half that of the inclosing V-shaped chamber —7—. Mounted within the chamber —7— is a solid V-shaped switch block —10—, formed with vertical walls, and 95 of a width approximately one half that of the inclosing V-shaped chamber —7—. The switch block —10— is preferably made of cast metal and is pivotally mounted by the pivot pin —11— securely attached thereto 100

and projects from the lower side thereof. Pivot pin —11— is mounted in the bearing —12— formed through the bottom wall of the casing —1— on the center line of the 5 groove recess —8— and chamber —7—, positioned near the pointed ends of said chamber and switch block, and in a manner that will allow said switch block —10— to be moved sidewise on the supporting pivot pin 10 and enter either half chamber, and at the same time open a clear passage way through the grooved recess —8— along one side of said switch block for the entire length of said casing —1—, and capable of forming said 15 clear passage on either side of said switch block, depending upon which half chamber into which it may be turned. Through the larger end —a— of the switch block —10— is formed a bar recess —13—, positioned horizontally and cross-wise through the said block, and carries mounted therein a horizontal rail point operating bar —14—. The operating bar —14— is pivotally attached thereto by the pin —15—, and is free to turn thereon. The said operating bar —14— is passed 20 through a wall port —16— formed through the outer wall of the casing —1—, and is extended to the free end of the rail switch point —6— and pivotally attached to said rail switch point by the clevis —17— and pin —18—. The clevis —17— being securely attached to the rail switch point —6— by the bolts —19—. The operating bar is of a 25 length that will allow a complete closing of the switch point —6— against the car rails —5— when the V-shaped switch block —10— is turned into the half chamber —7— next adjacent said rail switch point. Also will 30 completely open said rail switch point when said switch block —10— is turned to the opposite half chamber —7— on the side opposite the said rail switch point —6—. Securely attached to the front end of the car —20— as may be operated upon the tracks 35 —5—, and on the under side of said car is a rigid supporting frame —21—, the same being mounted thereon by the bolts —22—. The supporting frame —21— is positioned 40 vertically along the centerline of the car —20— and in true alignment with the centerline of the grooved recess —8— of the track casing —1—. Within the supporting frame —21— is mounted a strong switch operating bar —23—, positioned vertically therein and 45 slidably mounted within said casing through the bearings —24— and —25—. The switch operating bar —23— is extended at the upper end thereof a sufficient length to be passed 50 through the floor —26— of the car —20—, and is formed with an operating handle —27— on the top end thereof. Said handle —27— may be of a design to be conveniently used by the hand or by the foot as may be desired by the driver of the car. The lower 55 end of the switch operating bar —23— is

projected below the bottom of the said supporting frame —21—, and is formed with a forward thin edge —28— extending the entire length of the lower projected section. Said lower end of the bar —23— being positioned in true alignment with the centerline of the grooved recess —8— of the track casing —1—, and of a height to clear said casing —1— when the bar —23— is in its upper raised position, said bar —23— being capable of being lowered by the car driver sufficiently for engaging the grooved recess —8—, passing therethrough and at the same time engaging the switch block —10— on either side and forcing same into the one half 70 of the V-shaped chamber —7— of the track casing —1—, and thereby closing or opening the rail switch point —6— as the car —20— approaches on the tracks —5—, and without stopping the car. Should the switch block —10— and the rail switch point —6— be in the desired position, the car driver does not molest it or lower the switch operating bar —23—, but in case the switch rail is desired 75 to be changed in either direction, the same is accomplished by lowering said switch operating bar —23— which alternately engages the projected point of the switch block —10— which extends to the opposite casing wall and moves the switch block —10— alternately 80 from one side recess —7— to the other. Within the supporting casing —21— is mounted a heavy coil spring —29—, so attached to the switch operating bar —23— that same is held firmly in its upper position except when 85 forced downward by the car driver for operating the switch block. The lower bearing —25— of the supporting frame —21— is 90 formed of an elongated slot shaped opening to allow for a slight sidewise adjustment of the bar —23— when passing the pivoted center of the switch block —10— along either side thereof. The switch block —10— being 95 projected ahead of the supporting pivot —11— for engaging and directing the said bar —23— into the closed side of the grooved recess —8— for insuring the proper movement of the switch block and connected mechanism. 100

Having fully described my automatic rail switch operating device, what I claim as my invention and desire to secure by Letters Patent is:

1. A railway switch operating device adapted for automatically opening and closing a railway switch and used in combination with a track vehicle operating bar, comprising a hollow track casing having means for rigidly attaching same to the track ties between the double track rails, a V-shaped switch block pivotally mounted within said hollow track casing by a pivot positioned near the pointed end thereof, said switch block being capable of swinging sidewise within said hollow casing when engaged 115 120 125 130

by a single track vehicle operating bar, a switch point operating bar having one end pivotally attached to the movable end of said switch block, and means mounted on the opposite end of said operating bar for attaching same to a railway switch point.

2. A railway switch operating device adapted for opening and closing a railway switch and used in combination with a single track vehicle operating bar, comprising a hollow track casing suitable for rigidly mounting on the rail ties between the double track rails, said casing having a longitudinal opening formed along the top wall thereof of opening into said hollow casing chamber, a V-shaped switch block pivotally mounted within the hollow track casing by a pivot positioned near the pointed end of said block, said switch block being capable of sidewise movement within the hollow casing in either direction when engaged by a single rail vehicle operating bar, a switch point operating bar pivotally attached to the larger end of said switch block and movable therewith, and means mounted on the opposite end of said operating bar for attaching same to the free end of a railway switch point.

3. A railway switch operating device adapted for opening and closing a railway switch point and used in combination with a single track vehicle operating bar, comprising a track casing suitable for rigidly attaching same to rail ties between the double track rails, said casing being formed with a V-shaped chamber therein lengthwise thereof and having an upper wall slot opening the entire length thereof, a V-shaped switch block pivotally mounted within said V-shaped track casing chamber by a pivot bolt positioned near the pointed end of said switch block, said switch block being capable of swinging to either side of the track casing chamber when engaged by a single track vehicle operating bar, a switch point operating bar having one end pivotally attached to the larger end of said switch block and projected sidewise through the side track casing wall, and means mounted on the opposite end of said operating bar for pivotally attaching same to the free end of a railway switch point.

4. A railway switch operating device adapted for opening and closing a railway switch point automatically and used in combination with a single track vehicle operating bar, comprising a rectangular shaped track casing suitable for rigidly mounting on track ties between double track rails, said track casing being formed with an enlarged V-shaped chamber lengthwise thereof and provided with a wall slot opening along the top side extending the full length of said casing, a V-shaped switch block pivotally mounted within said casing V-shaped chamber by a pivot bolt positioned near the

pointed end of said block, said switch block being capable of swinging sidewise into either side of said casing chamber when engaged by the projected end of a single track vehicle operating bar, a switch point operating bar pivotally attached to said switch block near the larger end thereof and projected sidewise therefrom a side casing wall opening, and a pivoted bearing attached to the opposite end of said operating bar for attaching same to the free end of a railway switch point.

5. A railway switch operating device adapted for opening and closing a railway switch point automatically by an approaching rail vehicle, comprising a suitable track casing for fixedly and rigidly attaching to railway ties between double rail track, said track casing being formed with an enlarged V-shaped chamber positioned lengthwise thereof and provided with a straight narrow bar slot along the upper casing wall positioned along the V-shaped chamber centerline, a V-shaped switch block pivotally mounted within the track casing V-shaped chamber by a pivot bolt positioned near the said switch block point and in a plane through the center line of said casing recess and bar opening, the larger end of said switch block being capable of sidewise movement in either direction, in either half of the track casing, sufficient to provide a clear path at the opposite side thereof along one edge of the top casing bar slot for admitting a single track vehicle operating bar therein and at the same time placing the switch block point against the opposite casing bar slot wall, a switch point operating bar pivotally attached to the larger end of said switch block and projected sidewise therefrom through a side wall casing opening, means mounted on the opposite end of said operating bar for pivotally attaching same to the free end of a railway switch point, and a single track vehicle operating bar suitable for mounting on a track vehicle capable of being so depressed to engage with the casing bar slot and switch block for automatically moving said switch block and attached rail switch point from one side to the other.

In witness whereof I sign these specifications.

JOHN BOYKO.
